US0D1092735S

(12) **United States Design Patent** (10) **Patent No.:** **US D1,092,735 S**
Knecht et al. (45) **Date of Patent:** **** Sep. 9, 2025**

(54) **ALIGNMENT FEATURE**

- (71) Applicant: **Kenvue Brands LLC**, Summit, NJ (US)
- (72) Inventors: **Max Hunter Knecht**, Brooklyn, NY (US); **Stephen Anton**, Union, NJ (US); **Sean James Coyle**, Pennington, NJ (US); **Nathan Wald**, Summit, NJ (US); **Eleanor F. Small**, Philadelphia, PA (US); **Nicole Kaminsky**, Yardley, PA (US)
- (73) Assignee: **Kenvue Brands LLC**, Summit, NJ (US)

(**) Term: **15 Years**(21) Appl. No.: **29/821,388**(22) Filed: **Dec. 29, 2021****Related U.S. Application Data**

(63) Continuation of application No. 17/364,981, filed on Jul. 1, 2021.

Foreign Application Priority Data

Jul. 1, 2021 (WO) PCT/US2021/040042

(51) **LOC (15) Cl.** ..... **24-02**(52) **U.S. Cl.**USPC ..... **D24/137****Field of Classification Search**

USPC D24/137, 138

CPC A61B 1/227; A61B 1/00096

CLAIM

The ornamental design for an alignment feature for a display screen or a portion thereof showing my our design; and,

FIG. 1 is a perspective view of an alignment feature for a display screen or a portion thereof showing my our design; and,

FIG. 2 is a front view thereof.

The broken line showing is included for the purpose of illustrating unclaimed subject matter and forms no part of the claimed design.
